UNITED STATES PATENT OFFICE.

CARL A. BJORNSSON, OF WELLSVILLE, NEW YORK.

INTERNAL-COMBUSTION ENGINE.

Application filed October 26, 1922. Serial No. 596,940.

To all whom it may concern:

Be it known that I, CARL A. BJORNSSON, a citizen of the United States, and a resident of the town of Wellsville, county of 5 Allegheny, and State of New York, have invented a new and useful Internal-Combustion Engine, of which the following is a specification.

This invention relates to engines and particularly to internal combustion engines, and more especially to internal combustion engines of the Diesel type, and has particular reference to that type of Diesel engine in which the air for atomization of the fuel 15 is generated in the main working cylinder and caused to flow by a restricted orifice into the combustion chamber at the moment fuel injection takes place.

The primary object of this invention is 20 to provide a fuel atomizing device for use with an engine of the type specified which will most effectively and most finely atomize the greatest amount of the combustible fluid used for driving the engine.

25 Other objects and advantages will appear as the description of the particular physical embodiment selected to illustrate the invention progresses and the novel features of the invention will be particularly pointed out 30 in the appended claim.

In describing the invention in detail and the particular physical embodiment selected to illustrate the invention reference will be had to the accompanying drawing, and the 35 particular physical embodiment selected to illustrate the invention appearing therein, in which:

Figure 1 is a fragmentary vertical sectional view of an engine of the internal combustion type with my invention applied thereto; Fig. 2, is a fragmentary cross sectional view of a device embodying my invention in modified form; Fig. 3, is a cross sectional view on the plane indicated by 40 the line III—III of Fig. 2, viewed in the direction of the arrows at the ends of the line; Fig. 4, is a fragmentary cross sectional view of a device embodying my invention in another modified form; Fig. 5, is a cross 45 sectional view on the plane indicated by the line V—V of Fig. 4, viewed in the direction of the arrows at the ends of the line.

50 Referring first to Fig. 1, numeral 1, designates a portion of a working cylinder hav-

ing the cored out space 2, serving as a water circulating space or water jacket as is usual in internal combustion engines.

The cylinder 1, has a cylinder head 3, attached thereto by studs, as 4, and nuts, as 5. The head has the cored out space 6, serving as a water circulating space or water jacket as is usual in internal combustion engines.

Within the cylinder 1, is the usual piston 7, connected as is usual in such engines.

Attached to the center of the upper face of the piston 7, is an atomizer nozzle, designated as a whole by 8. This atomizer nozzle is attached to the piston in any suitable manner, preferably by forming on it a concentric projection 9, threading the same and screwing into a threaded orifice 10 of the piston. This atomizer nozzle has a flange portion 11, which is just slightly less in diameter than the diameter of the entrance or throat 12 of the combustion chamber 13, so that flange 11 will never bind in the throat 12, regardless of expansion and contraction.

80 The atomizer nozzle 8 is formed preferably with a shoulder 14, which bears against the piston 7 and is so positioned that when projection 9 is screwed in tightly with the shoulder 14 bearing against the piston, a space 15 will exist between the flange 11 and piston 7. From this space 15, lead ducts, as 16, which connect with a main conduit 17, terminating at the end of the nozzle 8.

85 The flange 15, fitting into the throat 12 of the combustion chamber causes a chamber 18 to be formed above the piston, so that at the moment fuel is injected through pipe 19, into the combustion chamber, compressed air is generated above the piston 7 and flowing through ducts 16 enters conduit 17 and issuing forcibly from the end of the nozzle impinges upon the stream of fluid issuing from pipe 19 and mechanically breaks it up and due to the turbulence caused by the in-rushing air flowing directly at the inrushing fluid causes the fluid to be extremely finely atomized and the cyclonic turbulence of the air in the closed combustion chamber completely and thoroughly and intimately mixes the atomized fluid with the combustion supporting air, so that when combustion starts, that is when detonation takes place, just about the time the piston reaches the upper limit of its travel, it is most efficient in that 90 100 105 110

the greatest possible utilization of fuel is had, due to its extremely fine atomization by the mechanical action and the complete and thorough mixing with the air due to 5 the great turbulence.

It will also be understood that by my invention the air for atomization of the fuel is generated in a chamber separate from the combustion chamber and reaches its highest 10 compression at such a moment that it is most effective for atomizing the injected fuel, especially as it issues from the chamber by a nozzle pointed directly or substantially directly at the stream of fluid fuel. 15 Furthermore the air enters the combustion chamber at the moment of fuel injection at a much higher velocity than it would if it had the entire throat 12 to flow through.

My invention permits the air in the cylinder and in the combustion chamber to be 20 both largely reduced in volume while a comparatively free passage exists between the cylinder and the combustion chamber, then in producing the remaining compression 25 necessary for ignition the combustion chamber and the cylinder are shut off from one another except through nozzle 8, and thus it is the most highly compressed air which is forced through nozzle 8, and air which 30 as regards the air of the combustion chamber is more highly compressed, so that it can so to speak make a pathway for itself through the air of the combustion chamber to the fluid issuing from 19, it is also of 35 course the air which is most highly heated so that its direction, velocity and temperature all combine to give most efficient atomization.

In Figs. 2 and 3 I have shown a modified 40 form of a device embodying my invention. This modification is constructed just as is the form shown in Fig. 1 except that instead

of a single conduit 17, as in Fig. 1, I have a plurality of conduits, 20 to 25 inclusive.

In Figs. 4 and 5 I have shown another 45 modified form of a device embodying my invention. This modification embodies a plurality of conduits, similar to the form shown by Figs. 2 and 3, but in the form shown by Figs. 4 and 5, the ends of the conduits 26 to 50 29 inclusive from which the air issues are inclined so that cross currents are produced.

Although I have particularly described one specific physical embodiment of my invention and explained the mode of operation thereof, and have described modifications thereof and explained the mode of operation thereof, nevertheless I desire to have it understood that the forms selected are merely illustrative and do not exhaust 60 the possible physical embodiments of the idea of means underlying my invention.

What I claim as new, and desire to secure by Letters Patent, is:

In an internal combustion engine, in combination: a working cylinder; a combustion chamber communicating therewith by a throat of relatively ample cross sectional area; a piston; a nozzle attached to the piston and having a flange approximating in 70 cross section that of the throat and positioned to enter the throat upon a stroke of the piston prior to the completion of the piston's stroke, said nozzle formed with a duct and means communicating therewith 75 forming a passage between the duct and the space in advance of the piston, the duct and the said means forming the sole passage for compressed air above the piston when the flange is within the throat and a fuel injection duct opening in the combustion chamber in a direct line with the first mentioned duct.

CARL A. BJORNSSON.
